(57) **CLAIM**

The ornamental design for an undercabinet plug-in mount, substantially as shown and described.

DESCRIPTION

FIG. 1 is a front, top, left-hand side perspective view of an undercabinet plug-in mount comprising a new, original and ornamental design;

FIG. 2 is a front view thereof;

FIG. 3 is a left-hand side view thereof;

FIG. 4 is a right-hand side view thereof;

FIG. 5 is a top view thereof;

FIG. 6 is a bottom view thereof; and,

FIG. 7 is a rear view thereof.

The broken lines shown in the drawings illustrate unclaimed portions of the article and form no part of the claimed design.
